UNITED STATES PATENT OFFICE.

FRED PARK STEVENS, OF DENVER, COLORADO, ASSIGNOR OF ONE-HALF TO JOHN ARTHUR EDDY, OF DENVER, COLORADO.

REGISTERING MECHANISM.

No. 888,667.

Specification of Letters Patent.

Patented May 26, 1908.

Application filed July 16, 1907. Serial No. 384,022.

To all whom it may concern:

Be it known that I, FRED PARK STEVENS, a citizen of the United States, residing at Denver, in the city and county of Denver and State of Colorado, have invented a new and useful Registering Mechanism, of which the following is a specification.

This invention relates to means for registering the number of prints made by a photographic printing machine but embodies mechanism that is useful for other analogous purposes.

The primary object of the present invention is to provide novel means of a simple and accurate character, whereby the number of prints and the number of dozens of prints made are registered, said mechanism being associated with operating means actuated by the printing mechanism.

20 The preferred embodiment of the invention is illustrated in the accompanying drawings, wherein:—

Figure 1 is a sectional view through a printing machine, showing the registering mechanism in elevation. Fig. 2 is a horizontal sectional view through the machine, showing the said registering mechanism in bottom plan. Fig. 3 is a top plan view of the register. Fig. 4 is a bottom plan view of the same. Fig. 5 is a side elevation thereof. Fig. 6 is an end view, illustrating the operating means. Fig. 7 is a longitudinal sectional view through the mechanism. Fig. 8 is also a sectional view. Fig. 9 is a cross sectional view illustrating the carrying mechanism when in operative position. Fig. 10 is a view similar to Fig. 9, but illustrating the carrying mechanism when in an inoperative position. Fig. 11 is a detail cross sectional view showing the locator and locator teeth.

Similar reference numerals designate corresponding parts in all the figures of the drawings.

In the embodiment illustrated, the mechanism is employed in connection with a photographic printing machine that constitutes the subject-matter of another co-pending application, Serial No. 383,984. No extended description of the machine is believed to be necessary. Suffice it to state that it includes a negative support or holder 12, beneath which operates a shutter composed of oppositely swinging sections 13. These shutter sections are mounted on rock shafts 14. Automatic mechanism, designated as a

whole by the reference numeral 15, is provided for effecting the opening and closing movements of the shutter, and the speed of said operating mechanism, which determines the length of the exposure, is controlled by 60 means of a rotary valve 16 mounted in a valve seat 17, which seat preferably constitutes an integral part of a dial plate 18 mounted on the top of the machine. This dial plate is provided with a scale 19, over 65 which operates the pointer 20 for determining the position of the valve. The said dial plate constitutes a support, and a cover for the registering mechanism, being provided with sight openings 21 and 22 through which 70 the numbers of the number wheels herein-after described, are successively displayed. Transparent material 23, such as celluloid or the like, preferably extends across the openings. In addition to the automatic 75 mechanism for operating the shutter, manual means is also employed for actuating the same, and as disclosed, particularly in Fig. 6, this means consists of a lever 24, fulcrumed between its ends on a bracket 25, that depends from the dial plate 18. The lower end of the lever is provided with a rack 26 that meshes with a pinion 27 carried by one of the shutter rock shafts 14. The other arm of the lever extends through a slot 28 in the dial 80 plate 18, and has a suitable knob 29. The mechanism thus far outlined is fully disclosed in the co-pending application to which reference has already been made.

Depending from the under side of the dial plates 18 are spaced brackets 30, in which is fixed a stationary shaft 31. Loosely journaled on this shaft is a wheel 32 having numbers on its periphery, which are exposed through the sight opening 22. The said 90 wheel is furthermore provided with teeth 33 projecting from the edge of the rim. A sleeve 34 is journaled on the shaft, and fixed to this sleeve is another number wheel 35, the numbers of which are successively exposed through the sight opening 21 on the elevation of said wheel. An actuating crank arm 36, pivoted on the shaft 31, contiguous to the wheel 35, is provided with a suitable dog 37 that coacts with ratchet teeth 38^a 105 formed in one margin of the edge of the wheel 35. The actuating arm 36 has a link connection 38 with a crank disk 39 on one of the shutter rock shafts 14. It will thus be evident that every time the shutter is opened, 110

the arm 36 will be drawn downwardly, and the dog 37 will ride over one of the teeth 38 of the wheel 35. When the shutter closes, the said dog 37 being moved upwardly, will 5 effect a movement of the wheel 35. Thus every time an exposure is made, the wheel 35 will be moved one increment, and consequently the numbers on said wheel will be successively displayed through the opening 10 21. These numbers run from zero to twelve, and the wheel 32 is employed for registering the numbers of dozens. Consequently upon every rotation of the wheel 35, the wheel 32 must be rotated one increment. To effect 15 the said movements of the wheel 32, a crank arm 39^a is fixed to the sleeve 34, and pivoted on said crank arm, is a dog 40 that is movable into and out of coaction with the wheel 33 of said wheel 32. A spring 41, mounted 20 on the arm 39^a, bears against a projection 42, carried by the dog, and serves to normally hold said dog out of coaction with the teeth. A pin 43 is, however, carried by the fixed 25 shaft 31 between the sleeve 34 and the wheel 32, and the free end of this pin is disposed in the path of movement of the rear side of the dog as disclosed in Fig. 9. It will thus be 30 evident that upon each rotation of the wheel 35, and consequently of the sleeve 34, the dog 40 will be carried into engagement with the pin 43, and said pin will force the dog outwardly so that it will engage one of the 35 teeth of the wheel 32. It will remain in engagement with said tooth long enough to effect a movement of the wheel 32 to sufficiently expose another number through the sight opening 22, but as soon as said dog 40 passes out of engagement with the pin 43, the spring 41 will react and carry the dog out of 45 coaction with the teeth. A locator spring 44, engaging between the teeth 33 of the wheel 32 serves to hold said wheel against accidental rotation, and another locator spring 45 engages in seats 46 formed in the sleeve 34, and in like manner maintains the wheel 35 against accidental movement.

It is believed that the operation of the mechanism will be clearly evident. Whenever the shutter opens, the actuating arm 36 50 will be elevated, causing the dog 37 to ride over one of the teeth 38^a of the wheel 35. When said shutter closes, the dog 36 is again depressed, effecting the movement of the wheel and a corresponding movement of the 55 arm 39. When said wheel has completed one revolution, which requires twelve increments of movement, the wheel 32 is moved one increment. Thus an accurate account of the number of prints made is obtained.

It often happens, however that the shutter 60 is opened manually, for instance for the purpose of inspecting the negatives, and in any such case, it is desirable that the registering mechanism be made inoperative. To secure 65 this desired result, a sliding stop 47 is mount-

ed on the dial plate 18 in suitable keepers 48, and is movable across a portion of the slot 28 or in other words into the path of movement of the actuating arm 29 of the lever 24. This stop thus prevents the full movement of the 70 lever, and while permitting it to move the shutter to open position, prevents the movement of the arm 36 sufficiently to allow the dog 37 to ride over the tooth. With this 75 stop 47 in operative position therefore the shutter can be opened and closed without effecting the actuation of the registering mechanism.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention. For instance in the embodiment disclosed, the number wheel 32 is provided with twelve numerals, but it 90 will be evident that any numbers may be employed as desired.

Having thus fully described my invention, what I claim as new, and desire to secure by Letters Patent, is:—

1. In mechanism of the character described, the combination with a shaft, of a number wheel rotatably mounted thereon, a sleeve journaled on the shaft at one side of the number wheel and having its adjacent 100 end spaced therefrom, a crank arm carried by said adjacent end, another number wheel fixed to the opposite end of the sleeve, means for rotating the second wheel and the sleeve, a dog carried by the crank arm and movable 105 into and out of coaction with the first wheel, means for normally maintaining it out of such coaction, and a post secured to the shaft between the first wheel and the adjacent end of the sleeve and located in the path of movement of the dog to move the latter into coaction with said wheel.

2. In mechanism of the character described, the combination with a shaft, of a number wheel rotatably mounted thereon, a 115 sleeve journaled on the shaft at one side of the number wheel and having its adjacent end spaced therefrom, a dog connected to the adjacent end of the sleeve and movable into and out of coaction with the first wheel, 120 means for normally maintaining it out of such coaction, a post secured to the shaft between the first wheel and the adjacent end of the sleeve and located in the path of movement of the dog, to move the latter into coaction with said wheel, said sleeve having an annular series of teeth between the dog and the second wheel, and a locator that engages the teeth.

3. In mechanism of the character de- 130

scribed, the combination with a shaft, of a wheel loosely journaled thereon and having a rim provided on one edge with spaced teeth, of a sleeve journaled on the shaft and having one end spaced from the wheel, a second wheel fixed to the sleeve, means for rotating the second wheel to rotate the sleeve, a crank arm carried by the end of the sleeve that is adjacent to the first wheel, a dog 10 mounted on the crank arm and yieldingly maintained out of coaction with the path of the wheel, a post fixed to the shaft between the first wheel and the adjacent end of the sleeve, said post having its outer end dis-

posed in the path of movement of the dog to 15 carry the same into coaction with the teeth of the first wheel, said sleeve having an annular series of teeth disposed between the crank arm and the second wheel, and a spring locator that engages the teeth. 20

In testimony, that I claim the foregoing as my own, I have hereto affixed my signature in the presence of two witnesses.

FRED PARK STEVENS.
